UNITED STATES PATENT OFFICE.

ARTHUR E. ENGLAND, OF AMESBURY, MASSACHUSETTS, ASSIGNEE TO EVERETT E. KENT, OF NEWTON, MASSACHUSETTS.

FASTENING DEVICE.

986,372.

Specification of Letters Patent.

Patented Mar. 7, 1911.

Application filed June 22, 1904, Serial No. 213,627. Renewed August 5, 1910. Serial No. 575,805.

To all whom it may concern:

Be it known that I, ARTHUR E. ENGLAND, of Amesbury, in the county of Essex and State of Massachusetts, have invented certain new and useful Improvements in Fastening Devices, of which the following is a specification.

This invention relates to improvements in fastening devices, and it is here shown as it may be applied in fastening cooling plates upon the cylinder of an internal combustion engine.

More particularly it relates to means for fastening two parts together in which a permanently tight fastening is required, and in which access to the fastening can be had from only one side.

The invention comprises the fastening hereinafter described, and illustrated in the accompanying drawings, in which—

Figure 1 represents one of the parts which is to be fastened, with places prepared for the fastening seen in plan view. Fig. 2 represents one use of the fastening in which a large number of cooling plates are fastened to an engine cylinder in close proximity to each other. Fig. 3 represents a section on the line 3—3 of Fig. 2, and Fig. 4 represents one of the plates shown in Figs. 2 and 3, being a view similar to Fig. 1.

Referring to the drawings:—*a* represents a cylinder forming a part of an internal combustion engine; and *b b* represent heat-radiating blades of sheet metal, each of which is provided at its inner edge with a flange *b'* seated upon the periphery of the cylinder *a*. The said flange is provided at suitable intervals with orifices *b''* which are preferably polygonal in shape, as shown in Figs. 1 and 4, these orifices receiving securing rivets *c c* which enter orifices formed for their reception in the cylinder and are upset at their outer ends to form heads *c'*. The orifices which receive the fastenings *c* are preferably screw-threaded and the said fastenings are made of screw-threaded wire each being inserted by rotating the wire until its end portion is entered in corresponding orifices and engages the thread thereof, after which the wire is severed above the flange *b'* and the projecting portion is upset and thus caused to form the head *c'* and to fill and closely fit the polygonal orifices *b''*. The polygonal form of

the orifices prevents the threaded fastening devices *c* from turning in the cylinder and thus becoming loosened. The blades *b* are preferably arranged in close proximity to each other and they radiate from the cylinder as indicated in Fig. 2, so that they furnish large areas of heat-dissipating surface.

By attaching the heat-radiating blades in the manner shown, and described, I avoid weakening the wall of the cylinder by the formation of grooves therein to receive the inner edges of the blades, as heretofore. The fastenings *c* may be located sufficiently far apart to avoid any considerable weakening of the cylinder.

The blades *b* extend longitudinally or lengthwise of the cylinder, as shown, so that air reaches all parts of the cylinder. They may be either straight, as shown in Fig. 4, or corrugated as shown in Fig. 1. If desired, the blades may be given a slight pitch or spiral inclination.

The use of this invention for the purpose illustrated shows one situation in which its use is highly advantageous. In such cases it is important to maintain a close connection between the engine cylinder and the plates for the sake of easy transmission of heat. The upsetting of the head joins the plate to the cylinder head as close as a rivet would do; and the expansion, or de-forma-tion of the head into non-circular form in the polygonal hole prevents rotation of the stud and thus, prevents its withdrawal. Thus a single headed rivet is formed which holds firm notwithstanding the inner end of the rivet is inaccessible. In the application of the invention here illustrated it is proposed to use a series of such studs between each plate and the cylinder. Of course the same principle can be applied to fastening any other bodies desired. If only one stud is to be employed in the fastening some means should be provided for preventing rotation of one body relative to the other about the stud. Another stud, or any kind of a lug would serve this purpose. In the drawings the use of a multiplicity of studs serves this purpose, the rotation of a plate about any one of them being prevented by the presence of the others.

I claim:

A joint comprising two bodies, one of

which has a screw threaded hole and the other a non-circular hole, and a stud, threaded in the first hole, passing through the second and engaging in its non-circular portion and being thereby prevented from rotating, the stud having a head on the remote side of the second body.

In testimony whereof I have affixed my signature, in presence of two witnesses.

ARTHUR E. ENGLAND.
